DEVICE FOR BURNING ATOMIZED LIQUID FUEL

Adolf Bargehoer, The Hague, Netherlands

Application March 9, 1934, Serial No. 714,791
In the Netherlands March 14, 1933

3 Claims. (Cl. 158—76)

This invention relates to a device for burning a mist of fuel, said mist being produced by pressure-atomizing. In devices of this type the combustion air flows directly around the spraying device to the flame and the ignition point of the flame is not stable.

Dependent on such factors as the draft, the spraying and the shape of the spraying nozzles in prior art devices, the flame formed floats as a cloud in the combustion chamber, making complete combustion impossible and causing the flame to become easily extinguished.

The object of the present invention is to eliminate these objections and is attained by providing inside the device, and directly around the spraying device, an air supply conduit or pipe. The combustion air flows outside this pipe through an element offering resistance to the flow of air, such as a set of concentrically arranged screw 20 blades, baffles, perforated plates, or the like. A quantity of air, which is regulated independently of the combustion air, flows into the inner pipe around the spraying device. This quantity forms only a small part of the combustion air. By 25 exact adjustment of this quantity of "inside air" it is possible to give a stable shape to the flame and the combustion will begin at an adjustable short distance from the spraying device.

Preferably, the end of the inside air pipe is of an 30 obtuse conical or streamlined shape. An opening angle larger than 60° is desirable in most cases. A very stable flame formation results when an obtuse cone is fitted around the nozzle of the spraying device which forms, together with the 35 conically shaped end of the inside pipe, a cone-mantle-shaped conduit for the inside air. Moreover, a slight super-pressure is developed at the tip of the spraying device instead of a depression or stagnant space which would otherwise arise 40 at this point by the deflection of the combustion air flow from the tip of the spraying device. Owing to this arrangement, breaking back of the flame on the spraying device and sooting and blacking of the spraying device and the ignition 45 electrodes are prevented.

Preferably, the width of the cone-mantle-shaped conduit which forms the end of the inner pipe is adjustable. This is accomplished by arranging the spraying device to slide in the inside 50 pipe. Thus the spraying cone may be shifted somewhat with respect to the outlet of the inside air pipe.

In accordance with the present invention the inside air is rotated around the axis of the spraying device. This is attained by surrounding the

spraying device with screw blades. These may be in the same or in the opposite direction to a screw fitted in the supply pipe for the combustion air.

In order to minimize the inevitable irregularities 5 in the spraying of the fuel it is desirable to arrange the spraying device so that it may be rotatably adjustable in the inside pipe.

If an air flow resistance, e. g., a screw, is fitted in the pipe in the path of the combustion air, the 10 inside air may be tapped off ahead of this resistance. A valve or the like may be used to adjust the flow. The air flowing through the conduit 1 may also be tapped off the main air pipe so that the air pressure in this conduit may remain 15 constant.

Figs. 1 and 2 are side elevations partly in section of two devices arranged according to the invention.

In Fig. 1, 1 is the motor driving the low-pressure ventilator 2 and the fuel pump 21. The air flows by way of the main supply pipe 3, throttle valve 4 to the combustion device 5. The latter consists of a tubular part 6 for the combustion air wherein inside pipe 7 is arranged for the inside air and is fastened by the supports 16 to the cover 17. These pipes form primary and secondary air conduits, respectively. The inside pipe 7 ends in the obtuse conical part 21 having 20 outlet opening 22. Inside of pipe 7 the spraying device 8 is surrounded by cone 30 which, together with the cone-shaped end 21 of pipe 7, forms a cone-mantle-shaped passage. The combustion air pipe 6 is provided with the screw blades 25 and 25 pipe 7 opens into the chamber ahead of it. The valve 14 is adjustable with respect to seat 15 of pipe 7 by means of screw 28 and button 29. The fuel supply pipes of the adjustable spraying device 8 are arranged in the cylindrical part 13 of cover 17, so that the spraying device is rotatably and shiftably adjustable with respect to the cone-shaped part 21. 30 35 40 45

The ignition transformer 26, leads 27 and electrodes 24 are indicated in Fig. 1.

Fig. 2 shows a variation of the construction of Fig. 1 in which the inside air is tapped off the main air pipe 3 ahead of throttle valve 4 by means of pipe 31 and connection 1'. The inside air is 50 adjustable by means of throttle valve 32 and the spraying device is adjustable with respect to the cone-shaped end 21 of pipe 7.

In special cases, e. g., in larger burners, screw blades may be arranged on the cone-shaped part 55

30 of the spraying device 8 and the entire pipe 7 may be shiftable in pipe 6.

Part of the combustion air may be supplied at some other place.

5 5. What I claim is:

1. In a device for burning a mist of atomized liquid fuel, a pressure spraying device for producing a mist of fuel, two air conduits coaxially arranged around said spraying device and opening

10 substantially in the plane in which the fuel is discharged from the latter, the outside air conduit supplying air to support combustion, the inside air conduit supplying air to stabilize the flame, a pressure device supplying air to both

15 conduits, baffle means within the outside air conduit for offering resistance to the flow of combustion air therethrough to keep the air pressure of the air discharged from this conduit at the point of ignition at a lower value than the pres-

20 sure of the air discharged from the inside conduit so as to secure different air velocities at the nozzle ends of said air conduits and thereby prevent the formation of a stagnant space at the ignition point adjacent the tip of the nozzle.

25 2. In a device for burning a mist of atomized liquid fuel, a pressure spraying device for producing a mist of fuel, two air conduits coaxially arranged around said spraying device and opening substantially in the plane in which the fuel is dis-

30 charged from the latter, the outside air conduit supplying air to support combustion, the inside air conduit supplying air to stabilize the flame, a pressure device supplying air to both conduits, means including a valve for controlling the flow

35 of air through said inside conduit, means within

the outside air conduit for offering resistance to the flow of combustion air therethrough to keep the pressure of the air discharged from this conduit at the point of ignition at a lower value than the pressure of the air discharged from the inside conduit so as to secure different air velocities at the nozzle ends of said air conduits and thereby prevent the formation of a stagnant space at the ignition point adjacent the tip of the nozzle.

3. In a device for burning a mist of atomized 10 liquid fuel, a pressure spraying device for producing a mist of fuel, two air conduits coaxially ar-

15 ranged around said spraying device and opening substantially in the plane in which the fuel is dis-

charged from the latter, the outside air conduit 15 supplying air to support combustion, the inside

air conduit supplying air to stabilize the flame, a pressure device supplying air to both con-

duits, means in said inside air conduit for swirling 20 the air therein, means including a valve for con-

25 trolling the flow of air through said inside air conduit whereby a stable flame is produced at a

20 point in close proximity to said nozzle and means within the outside air conduit for offering re-

25 sistance to the flow of combustion air there- through to keep the pressure of the air discharged

30 from this conduit at the point of ignition at a lower value than the pressure of the air dis-

charged from the inside conduit so as to secure 30 different air velocities at the nozzle ends of said

air conduits and thereby prevent the formation 35 of a stagnant space at the ignition point ad-

jacent the tip of the nozzle.

ADOLF BARGEBOER. 35
